UNITED STATES PATENT OFFICE

109,763

DESIGN FOR A BOTTLE OR SIMILAR ARTICLE

Robert A. Kelly, East Pittsburgh, Pa., assignor to United States Glass Company, Pittsburgh, Pa., a corporation of Pennsylvania

Application February 23, 1938, Serial No. 75,232

Term of patent 3½ years

To all whom it may concern:

Be it known that I, Robert A. Kelly, a citizen of the United States, residing at East Pittsburgh, county of Allegheny in the State of Pennsylvania, have invented a new, original, and ornamental Design for a Bottle or Similar Article, of which the following is a specification, reference being had to the accompanying drawing, forming a part thereof, in which—

Figure 1 is a side view in elevation of a bottle or similar article showing my new design;

I claim:

The ornamental design for a bottle or similar article, substantially as shown and described.

ROBERT A. KELLY,
